UNITED STATES PATENT OFFICE.

WILLIAM A. PRYOR, OF SAVANNAH, GEORGIA.

RAINY-DAY-TABLET SHIELD.

Application filed March 11, 1926. Serial No. 93,993.

This invention relates to devices for shielding writing boards or pads from the rain and the general object of the invention is to provide a very simple, light, and easily handled device of this character adapted to be disposed over a writing board or tablet and engaged therewith, and so formed that the hand may be inserted through one side of the device so that writing may be placed upon the tablet or board, the invention being particularly adapted for use by railroad employees in checking the numbers of cars.

A further object is to provide a device of this character which may be cheaply made and readily handled.

My invention is illustrated in the accompanying drawings wherein:—

Figure 1 is a perspective view of a writing tablet or support with my shield protector applied thereto;

Fig. 2 is a face view of the translucent shield by itself;

Fig. 3 is a perspective view of the cover;

Fig. 4 is a fragmentary perspective view of one edge of the cover showing a modified form of clip.

Referring to these drawings it will be seen that my device comprises a supporting frame consisting of a longitudinally disposed strip 10, preferably of light metal or other material might be used for this purpose, and from which extend upwardly and laterally a plurality of frame strips 11, so that these strips constitute in effect a half arch. The extremities of these strips 11 remote from the longitudinal strip 10 are connected by a longitudinal strip 12. Projecting from the strip 10 at right angles thereto and in the same plane therewith, is a supporting strip 13. The longitudinally extending strip 10 is provided with a flange 14 and the strip 12 is provided at intervals with projecting studs 15 for a purpose to be later stated.

Projecting downward from one of the end strips 11 is a hood 16 of sheet metal or any other suitable material. The material of this hood is extended at one end as at 16^a, so as to join and be attached to the strip 13, thus constituting a brace supporting the frame formed by the members 11 and 12. The strip 10 is adapted to be disposed upon the margin of the writing board 17, or a board supporting a tablet, with the flange 14 engaged against the edge of this board, as

shown in Figure 1. This board 17 may be of paste board as usual, or it may be of thin wood or any other suitable material, and is provided with the usual clip 17^a at its upper end whereby sheets of paper may be held upon the board.

Adapted to be disposed over the frame formed by the strips 11, 12 and 13 is a cover of translucent or transparent material, preferably constructed as illustrated in Figure 3, and preferably constructed of celluloid, isinglass, or the like. This as illustrated, consists of a sheet of celluloid 18 bound at its margins by leather 19. This sheet of celluloid is adapted to be disposed over the frame formed by the strips 11, 12 and 13 and may be detachably engaged therewith in any suitable way. Thus, the supporting frame, as illustrated in Figure 1, might be provided with outwardly projecting studs 15 and the cover might have sockets 20 engageable with said studs. I have illustrated the studs 15 as being mounted upon clips 21 of common construction adapted to be slipped upon the longitudinal member 12. I do not, however, wish to be limited to this. In Figure 4 I have shown the margin of the cover 18 as being provided with hook-shaped clips 20^a to engage with the member 12. It will be seen that the celluloid sheet 18 when in place constitutes a cover which is supported so as to extend upwardly and laterally over the tablet supporting board 17 and form the cover for said board and for the tablet, which cover is open entirely along one end and along one side so as to permit the insertion of an arm into the shield beneath the cover and from one side and not require that the arm shall be inserted only through one end of the shield. The hood 16 has its lower edge spaced from the board 17 so as to permit the left hand to grasp the upper edge of the board while the board 17 rests upon the left arm and the board held so that the right forearm may be inserted beneath the cover or shield and used in writing. This hood prevents rain from striking downward upon the left hand and upon that portion of the tablet adjacent to what may be termed the upper end of the shield.

Preferably the cover 18, formed of celluloid with the binding strips 19, is provided at one end with a downward and lateral extension 22 or flap which extends downward over the upper margin of the hood 110

and thus prevents rain from striking inward between the translucent cover and the upper edge of the hood.

In the use of this device if it be desired 5 to jot down upon the tablet of paper on the board certain numbers as for instance, car numbers, which work must be done in the open and under all sorts of weather conditions, the supporting frame is disposed flat 10 upon the tablet and may be either clamped thereto by means of the clamp 17^a or simply rest thereon and the hand is inserted through the side of the supporting frame and the notes are made upon the tablet. 15 The translucent cover 18 gives ample light so that the writer may see what he is doing and at the same time rain or snow is kept off of the tablet itself.

The device is so constructed that it may 20 be readily held in one hand when no writing is being done thus leaving the other hand free to use a lantern. This device while particularly designed for the use of trainmen in checking cars, it is not limited to 25 this use as it might be used wherever it is desirable to take outdoor notes in rainy or snowy weather.

I have illustrated an embodiment of my 30 invention which I have found to be particularly effective, I do not wish to be limited thereto as many changes might be made in the details without departing from the spirit 35 of the invention as defined in the appended claims.

35 I claim:—

1. A shield for writing tablets comprising 40 a base frame adapted to rest flat upon a tablet supporting board, the frame having cover supporting members extending from one side of the base frame and arching laterally and upward over the same and terminating in a plane above the base frame, 45 a cover of translucent material supported by said members, and a hood extending down-

ward and outward at one end of the cover 45 and having its lower edge spaced from the end of the base frame to permit the insertion of the fingers.

2. A shield for writing tablets comprising 50 a supporting base adapted to be associated with a writing tablet, a transparent cover supported by the base and extending upward and laterally, the shield being entirely open at one end and along one side whereby to permit the insertion of the arm and hand 55 of a writer, and a hood extending downward at one end of the cover and having its lower edge free from attachment whereby to permit the other hand of the writer to hold the tablet.

3. A shield for writing tablets including 60 a cover supporting base adapted to be associated with a writing tablet, the base including a cross bar adjacent one end thereof, and a transparent cover extending upward and laterally from the base, the shield being entirely open at one end and along one side whereby to permit the insertion of the hand and arm of a writer, the shield being formed to provide a hood extending downward from 65 the cover and spaced from the cross bar whereby to permit the introduction of one hand of the writer and the support of the tablet.

4. A shield for writing tablets including a 70 tablet support and a cover of transparent material extending over the same and supported thereby, the shield including a hood 75 extending downward from the cover at one end thereof, and spaced from the tablet support to permit the insertion of the hand between the tablet support and the lower edge 80 of the hood, and the cover being open from one end to the other along one side and open at the end opposite said hood.

In testimony whereof I hereunto affix my 85 signature.

WILLIAM A. PRYOR.
